[57] CLAIM

The ornamental design for a lure, as shown and described.

DESCRIPTION

FIG. 1 is a front elevational view of lure embodying the new design thereof;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a top, front, and right side perspective view thereof; and,

FIG. 8 is a bottom, rear, and right side perspective view thereof.

Both treble hooks, the streamer, all three metal eyes, and any support surfaces visible in phantom lines in the figures are hereby disclaimed and form no part of the claimed design.
